UNITED STATES PATENT OFFICE.

GEORGE SNELL, OF THOMPSONVILLE, MICHIGAN.

SLEIGH.

SPECIFICATION forming part of Letters Patent No. 727,472, dated May 5, 1903.

Application filed October 6, 1902. Serial No. 126,165. (No model.)

To all whom it may concern:

Be it known that I, GEORGE SNELL, a citizen of the United States, residing at Thompsonville, in the county of Benzie and State of Michigan, have invented certain new and useful Improvements in the Construction of Sleighs; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in sleighs; and it consists in the provision of a sleigh the essential features of which comprise a knee and supporting members, the object of which is to give a sleigh strength enough to be used for heaviest logging purposes, light and neat, with mobility of respective parts, allowing the sleigh to adapt itself to the unevenness of roads, with no parts to crowd the snow and cause heavy draft and with the runner so supported that it is practically impossible for it to break in the center, with bunk-pins so protected and relieved of strain that they cannot easily be bent, and with the runner so controlled by the brace that it cannot get out of true line and constructed of such materials as will render a sleigh strong, efficient, and durable and unlikely to be broken by any sudden jar or strain.

The invention consists, further, in various details of construction and combinations of parts, as will be hereinafter more fully described and then specifically defined in the appended claims.

The present invention is clearly illustrated in the accompanying drawings, which, with the letters of reference marked thereon, form a part of this application, and in which drawings similar letters of reference indicate like parts in the views, in which—

Figure 1 is a perspective view of my improved sleigh. Fig. 2 is a vertical sectional view through one of the runners. Fig. 3 is a cross-sectional view through the sleigh, and Fig. 4 is a detail view of one of the braces. Fig. 5 is a detail view of one of the knees.

Reference now being had to the details of

the drawings, A A designate the runners of the sleigh, which are provided with metallic shoes B, and mounted upon each runner is a knee C, which is made preferably of the shape shown, and D designates binding-bolts, the heads of which are forced through the shoes, runners, and knees, the heads of said binding-bolts being preferably countersunk in the shoes, and retaining-nuts D' fitted over the threaded ends of the bolts for the purpose of holding the knee securely upon the runner. Two registering apertures E are formed through each runner and knee mounted thereon, through which apertures the bunk-pins E pass, which latter are adapted to rest upon the upper surface of the shoe, and each projects a suitable distance above the upper marginal edge of the knee and the metallic protecting-plate fastened thereto to receive the bolster F. Said bolster has two apertures which are brought into registration with the apertures formed in the knee and runner, and in adjusting the parts in place said bolster is fitted over the bunk-pin in the manner illustrated, with the upper portion of each bunk-pin projecting above the upper surface of the bolster for the purpose of receiving the metallic brace-bar G, which is bowed over the bolster and knee, with said contracted ends projecting through apertures in said brace. The ends of the brace-bar G are secured at G' to the runner in the manner shown. It will be observed that the undersurface of the bolster is slightly convexed and also the upper surface of the protecting-plate C', upon which it rests, thus allowing the bolster to give slightly and take up sudden jar. Each knee has an elongated aperture M, through which one end of a brace K passes, which brace is provided with a flange K', adjacent to the end which passes through the slot M in said knee, which flange is adapted to fit flat against the inner protecting-plate N, fastened to the inner faces of the knee and runner in any suitable manner. It will be observed that said slot M is slightly curved, whereby the end of the brace may have a movement therein. A washer L is mounted on the outer end of said brace and is adapted to bear against the outer face of the knee and held thereon by means of a key Q, which is passed through an aperture in the ends of the brace. The inner

end of the brace is flattened, as shown at R, and bolts O are passed through said flattened portion and through the bolster F, whereby the inner end of each brace may be held securely thereto.

From the foregoing it will be seen that a sleigh made in accordance with my invention will be strong and durable, making a rigid runner which will stand heavy strain and one in which the various parts are securely and compactly held together, the parts being allowed to give slightly by means of the construction and combination of the various parts.

While I have shown and described a construction embodying the features of my invention, it will be understood that I may make alterations in the detail construction of my invention without departing from the spirit of the invention.

Having thus fully described my invention, what I claim as new, and desire to secure by Letters Patent, is—

1. In a sleigh, the combination of the runners, a protecting-plate secured thereto, knee-blocks mounted thereon and provided with horizontal and slightly-curved slots, a bolster resting upon said blocks, braces fastened at their inner ends to said bolster, their outer ends passing through said slots, integral flanges on said braces adapted to bear against said protecting-plate, and the key and washer on the end of each brace, whereby the same are held in the slots in the knee-blocks, as set forth.

2. In a sleigh, the combination of the runners, the knee-blocks mounted thereon and having elongated slots thereon, a protecting-plate secured to the upper face of each knee-block and slightly convexed on its upper surface, a bolster having a slightly-convexed surface resting upon said protecting-plate, braces secured to the under surface of the bolster and having ends passing through said slots, a flange on each of said braces, bunk-pins passing through each runner and knee-block and bolster, and a brace-bar secured at its

ends to the runner and engaging the upper ends of the bunk-pins, as set forth.

3. In a sleigh, the combination of the runners, shoes mounted thereon, knee-blocks mounted thereon with retaining-pins, a protecting-plate mounted on each knee-block and having a slightly-convexed upper surface, bunk-pins passing through registering apertures in the knee-blocks and runners and resting upon the shoe of the runner, a bolster having a slightly-convexed under face resting on the protecting-plate, and apertures to receive the bunk-pins and brace strips or bars fastened to the runners and engaging the upper ends of the bunk-pins, braces carried by the bolster and passing through slots in the knee-blocks, and means for holding the same in place, as set forth.

4. In a sleigh, the combination of the runners, the shoes thereon, knee-blocks bolted to the shoes and runners, a protecting-plate mounted on each knee-block and having a slightly-convexed upper surface, bunk-pins passing through registering apertures in said runners and knee-blocks, the upper end of each bunk-pin being contracted, a bolster slightly convexed on its under surface and resting upon said protecting-plate and through which the bunk-pins pass, the brace-bar fastened at its ends to the runner and having apertures to receive the contracted ends of the bunk-pins, the curved braces fastened at their inner ends to the under surface of the bolster and having their outer ends passing through slots in said knee-blocks, flanges on said braces, protecting-plates fastened to the inner faces of the knee-blocks and runners, and a key to hold the outer ends of the braces in said slots, substantially as shown and described.

In testimony whereof I affix my signature in presence of two witnesses.

GEORGE SNELL.
